FREDERICK SAUER, OF FAIRFIELD, CONNECTICUT, ASSIGNEE TO THE KILBORN-SAUER COMPANY, OF FAIRFIELD, CONNECTICUT, A CORPORATION OF CONNECTICUT

REAR-VISION-MIRROR BRACKET

Application filed December 2, 1929. Serial No. 411,177.

My invention relates to a new and improved bracket for supporting a rear vision mirror on the upper front door hinge of an automobile on the driver's side in such a way that it will be securely held against displacement by the vibration of the vehicle and also by the opening and closing of the door. Heretofore, such devices have been mounted on the ends of the hinge pin of such a hinge, but since the ends of such a hinge pin afford but a minimum of holding surface, displacement of the bracket and a corresponding misadjustment of the rear vision mirror has been common.

One of the main objects of my invention is to provide a construction whereby a much greater surface is afforded for the support of the bracket so that displacement after application and adjustment is effectively resisted.

In the accompanying drawings—

Fig. 1 is a rear elevation of my bracket as applied to a hinge, certain parts being in section;

Fig. 2 is a fragmentary view partly in section on the line 2—2 of Fig. 1;

Fig. 3 is a view similar to Fig. 1 showing a modification.

1—1 represents the two stationary end hinge knuckles of a door hinge. 2 represents the intermediate rotatable hinge knuckle. 3 represents the usual hinge pin which passes through the several hinge knuckles in the usual way and upon which the knuckle 2 rotates.

In one form of my improved bracket, shown in Figs. 1 and 2, I provide an integral yoke member 4 which has an arm 5 projecting laterally therefrom for supporting a rear vision mirror 6, or any other suitable device. The upper arm 7 of the yoke 4 is provided with a passage for the hinge pin 3. This passage may be open at one side, as plainly seen in Fig. 2, to form a hook so that when the hinge pin is pushed up slightly to provide clearance above the upper hinge knuckle, this upper arm 7 may be hooked around the pin underneath the pin head which may then be knocked down so as to rest on the upper side of the arm 7 as shown in Figs. 1 and 3.

This obviates the necessity of entirely removing the pin 3 to apply the bracket. It will be noted that in this position the lower end of the pin 3 stands slightly retracted within the lower stationary knuckle so as to leave a recess therein. 8 is a clamping screw in the lower arm 9 of the yoke. This clamping screw preferably has a slight projection 8^a at its center which is adapted to extend slightly into the bore in the lower end of the lower hinge knuckle when the parts are assembled. The projection 8^a which extends slightly into the bore of the lower hinge knuckle prevents lateral displacement of the lower end of the yoke from the hinge. A check nut 10 on the clamping screw 8 may be provided, if desired. It will now be seen that when the bracket is applied to the hinge as shown in Fig. 1, the upper arm 5 of the bracket takes a broad firm bearing against the upper hinge knuckle around the pin passage, thus resisting any turning movement of the bracket on the hinge. Lateral movement is prevented by the pin 3 which passes through this arm 5. The clamping means 8 likewise takes a broad bearing against the lower hinge leaf around the pin passage, thus resisting a turning movement of the bracket on the hinge and corresponding displacement thereof, while the projection 8^a prevents the lower end of the yoke from being pulled off laterally from the hinge. It is, of course, immaterial whether the head of the pin 3 bears upon the upper end of the arm 5; since when the parts are assembled the yoke is clamped tightly on the two extreme ends of the end knuckles 1—1 of the hinge.

In the modification shown in Fig. 3, the yoke is formed in two parts 4^a—4^b, and the upper end of the part 4^a may be shaped to correspond with the upper end of the yoke shown in Figs. 1 and 2, while the lower end 4^b is slidable upon a clamping screw 11, which latter is carried by the yoke part 4^a. 11^a is a clamping nut on screw 11. The lower arm of the lower yoke piece 4^b is shaped to fit against the lower end of the lower hinge knuckle and preferably has a slight central projection 12 which extends correspondingly

into the bore of the lower hinge knuckle when the parts are assembled, performing the function of the projection 8^a on the screw 8 (shown in Fig. 1). To assemble the parts shown in the modification, the clamping nut 11^a is backed off until the two yoke sections 4^a—4^b may be spread apart sufficiently to let their ends embrace the ends of the hinge to which the bracket is to be attached. The upper section 4^a is then applied to the upper end of the upper hinge knuckle, as in Fig. 1, while the lower section 4^b is applied to the lower end of the lower hinge knuckle. The clamping nut 11^a is then screwed up until the two parts 4^a—4^b of the yoke grip on the ends of the hinge in the proper adjusted position of the bracket, which is then firmly held against displacement by the relatively large frictional surface engagement of the ends of the yoke on the ends of the hinge knuckles.

From the foregoing, it will be seen that in both forms of the bracket a maximum resistance to the turning movement is afforded so that the bracket will be effectively held in the proper angular adjustment while lateral disengagement of the bracket is absolutely prevented until the clamping means is backed off sufficiently to permit the projection 8^a, in the first instance, and 12, in the second instance, to be removed from the pin passage in the lower knuckle.

I claim:

1. A bracket support for attachment to a hinge comprising, a yoke having ends overstanding the end knuckles of a hinge and means to clamp said bracket to the outer ends of said end knuckles around the pin passage therein, the upper end of said bracket having a passage to receive that part of the hinge pin underneath the head thereof to hold the upper part of said yoke from disengagement from the hinge in a lateral direction, said passage being open at one side.

2. A bracket support for attachment to a hinge comprising, a yoke having ends overstanding the end knuckles of a hinge and means to clamp said bracket to the outer ends of said end knuckles around the pin passage therein, the lower clamping means of said bracket having an extension projecting slightly into the pin passage at the lower end of said lower hinge leaf.

3. A bracket support for attachment to a hinge comprising, a yoke having ends overstanding the end knuckles of a hinge and means to clamp said bracket to the outer ends of said end knuckles around the pin passage therein, the upper end of said bracket extending around the hinge pin underneath the head thereof to hold the yoke from disengagement from the hinge in one direction, the lower clamping means of said bracket having an extension projecting

slightly into the pin passage at the lower end of said lower hinge leaf.

4. A bracket support for attachment to a hinge comprising, a one-piece yoke having ends overstanding the end knuckles of a hinge, the upper end of said yoke having a pin passage for the hinge pin, a movable clamping member at the lower end of said yoke for engagement with the lower end of the lower hinge knuckle around the pin passage therein, said clamping member having a portion to extend slightly into the lower end of said pin passage.

5. A bracket support for attachment to a hinge comprising, a one-piece yoke having ends overstanding the end knuckles of a hinge, the upper end of said yoke having a pin passage for the hinge pin, a movable clamping member at the lower end of said yoke for engagement with the lower end of the lower hinge knuckle around the pin passage therein and having a portion to extend slightly into the lower end of said pin passage.

6. A bracket support for attachment to a hinge comprising, a clamping yoke having its ends arranged to overstand the outer ends of the end knuckles of a hinge, one end of said yoke having a pin passage for the hinge pin, a clamping part at the other end of said yoke for engagement with the outer part of the hinge knuckle adjacent thereto, one of the two last mentioned parts having a recess to receive within it a projecting portion of the other part to prevent lateral displacement of said yoke.

FREDERICK SAUER.
